STARTING BIT FOR ROTARY MASONRY BITS

Warren M. Bacon, Cleveland Heights, Ohio, assignor of one-half to Oliver P. Link, Cleveland, Ohio

Application March 14, 1951, Serial No. 215,594

5 Claims. (Cl. 255—69)

1

This invention relates generally to rotary bits, and more particularly, to a starting bit or tool, adapted to initiate a piercing or cutting operation in such hard granular structures such as concrete, brick and the like. More specifically, my invention is adapted to be attached to and used with, masonry drill bits of the type having a cylindrical body with a disc shaped head of concentric, external circumference, fixed on the operating end of the body, and provided with cutting members or teeth positioned radially on the face of the head perpendicular to the axis of rotation, while screw threads on the exterior of the body function to remove material cuttings from the hole being drilled. The type of bit above referred to is illustrated in United States Letters Patent No. 2,506,474, issued to Carl V. Tilden on May 2, 1950.

In using the above type of rotary bit to pierce a masonry wall, the initial opening in the wall before using the drill, in conventional practice, is made by a hand chipping tool, which is a time consuming operation, furthermore it is difficult to accurately center the initial opening at the desired part by this means and such operation frequently results in fracturing or splitting the masonry adjacent thereto. I have discovered that the initial piercing operation can be accomplished by providing a pointed removable starting tool adapted to be readily connected to and detached from, a rotary bit with the rear of the cutting head locking with the cutting members disposed on the head of the drill.

An object of the invention is to provide a removable starting tool to initiate a piercing operation for a masonry drilling operation, which can be quickly and easily attached to and detached from a conventional drill without altering the same.

Another object is to provide a starting tool which can start a hole at the exact point desired without chipping the sides thereof.

Other objects are to provide a durable, low cost starting drill, which can be easily sharpened, is adapted to initiate masonry piercing operations for a relatively wide range of hole diameters, and is adapted to be operated in various positions.

These and other objects will appear in the course of the following illustrative embodiment of the invention.

In the drawings forming a part of this description:

Fig. 1 is a side view of a masonry drill adapted to receive the starting tool;

2

Fig. 2 is a separate side view of the starting tool;

Fig. 3 illustrates the starting tool inserted in a masonry drill;

Fig. 4 is an end view illustrating the starting tool inserted in a rotary drill;

Fig. 5 is a central longitudinal section taken through Fig. 3, showing the device in a masonry piercing operation;

10 Fig. 6 is an enlarged side end view of the starting tool;

Fig. 7 is an end view of the device shown in Fig. 6;

15 Fig. 8 is a partial side view of a modified form of the invention; while

Fig. 9 is an end view of the device shown in Fig. 8.

For the drawings the numeral 10 refers to a cylindrical body having an axial bore 11, closed 20 at the trailing end by an integral shank 12 portion adapted to be rotated on its longitudinal axis by a suitable motor. The distal end of the body 10 is enlarged forming an annular head 13 having teeth 15, disposed on the face 14 thereof, 25 said teeth 15 being provided on one side with a shoulder portion 15a disposed approximately at right angles to the plane of the face 14, which preferably are four in number and are made of cemented carbide, or other suitable cutting materials and are positioned on the face 14 in such 30 manner that cutting edges are approximately radial to the head 13, while their outer ends project outwardly from the periphery of the head 13 and their inner ends project into the bore 11.

35 A continuous spiral thread 17 on the outer surface of the body 10, preferably square in cross section, provides means for carrying away masonry cuttings, and extends from a point near the head 13 to the proximal end of the body 10, while an annular groove 18, adjacent the head 13, permits the finely comminuted particles to pass from the outer ends of the teeth 15 to the spiral thread 17. The periphery of the head 13 may be flattened at 19, if desired, to form channels in advance of teeth 15.

40 A slot 21 extending longitudinally of the body 10 from where it intersects annular groove 18 to a point near the proximal end of the body 10, 45 communicates with the bore 11 and interrupts the thread 17, providing a passage supplementary to the slot 21, for conducting granular material from the bore 11 to the thread 17 along the major part of the latter. A shallow longitudinal groove 22 extending in continuation of the 50 slot 21 to the proximal end of the body 10 pro-

vides a passage supplementary to the slot 21 or to that passage provided by thread 17, by which the drilled-out material reaches the area around the shank 12.

When the shank 12 is rotated, the teeth 15 are adapted to cut an annular channel in a masonry structure while the inner ends of the teeth 15 projecting into the bore 11, operate to grind up the core as it is formed. The projection of the outer ends of the teeth beyond the outer periphery of the head 13 causes the channel thus bored to be slightly oversize and thus prevents the bit from binding as it progresses inwardly.

Finely comminuted material, passes through the flattened portion 19 of the head 13 to an annular groove 18 and then to spiral thread 17 by which it is moved from the hole. Particles dislodged at the face of the hole will enter the bore 11 through the open end thereof between the inner ends of the teeth 15, to be subjected to the grinding action of the teeth 15, thus breaking up the core as it is formed, while slot 21 permits the material to be thrown by centrifugal force outwardly of the side of the bit at that part of the slot projecting from the hole. The slot 21 also permits immediate discharge to the thread 17 of a part of the removed material suited in size for passage therealong. If the material is too large to enter the thread 17, it is ground against the wall of hole until suitably comminuted. Material entering the thread 17 is conveyed to the face of the masonry structure or, if the entire body of the bit has entered the hole, to the zone around the shank 12. The groove 22 at its points of intersection with the thread 17 provides sharp edges whereby any large particles traveling to the outer end of the bore may be further comminuated.

The device heretofore described relates to a known type of drill currently being used. My starting tool, adapted to be used with the foregoing drill, indicated by the numeral 23, comprises a shank 24, having an integral head 25, while a pointed cutting member 26 of suitable material such as tungsten carbide or the like, slopes rearwardly to side portions 27 terminating at the shank 24. The rearwardly sloping sides of the cutting member 26 and side portions 27 constitute shoulders. If desired the cutting member 26 may be formed of the same material as the teeth 15 disposed on the face 14 of the head 13 of the body 10. The starting tool above described is illustrated in Figs. 1 through 7.

A modified form of my invention illustrated in Figs. 8 and 9 corresponds in a general way to the form above described but differs therefrom in the provision of slots 28 disposed on the face 14 of the head 13, adapted to seat the rear ends of side portions 27 of cutting member 26. If desired, the rear end of the side member 27 may be especially shaped and formed to fit into the slots 28.

My starting tool 23 is adapted to initiate a cutting or piercing operation for the drill herein illustrated, the shank 24 thereof being inserted into the axial bore 11 of the body 10 as illustrated in Figs. 3, 4 and 5, with the side members 27 of the cutting member 26 resting against and retained by the sides of the teeth 15. The body 10 is then caused to rotate on its longitudinal axis by means of an electric motor operatively connected to the shank 12 thereof. The point of the cutting member 26 is pressed against the masonry at the point to be pierced, and continued rotation will advance the head 25 into the masonry until an opening has been cut corresponding in diameter to ap-

proximately the diameter of the face 14 of the head 13. The starting tool 23 is then lifted out of the axial bore 11 of the drill body 10 and the drill is then operated as heretofore described, to drill a hole of desired size in the masonry.

When the starting tool is in position it will be noted that the head member 24, which is substantially cone-shaped, fits between and is centered by inner edges of the four teeth 15. Also, that, as the body member 10 is turned while urging the starting member into the masonry work, the side portions 27 of the cutting member 26 are firmly forced against the shoulders 15a of the teeth 15. Thus, the starting tool is centered and retained without any additional securing means. It will also be seen that by so centering the cone-shaped head 25 by the teeth 15, which project somewhat into the bore 11 as above mentioned, a desirable clearance space between the head 25 and the entrance to the bore 11 is provided.

The starting tool illustrated in Figs. 8 and 9 is secured to the face 14 of the head 13 by seating the side members 27 of the cutting member 26 in the slots 28, which provides satisfactory locking means for certain types of work.

It will be apparent to those skilled in the art that the invention disclosed herein, may be variously changed, used or modified, without departing from the spirit of the invention or sacrificing the advantages thereof, and that the embodiment of the invention herein is illustrative only, and that my invention is not limited thereto.

I claim:

1. In a rotary bit for drilling concrete and the like, of the class including an elongated bored cylindrical body having a head at its leading end provided with a plurality of generally radially disposed cutting members including shoulder portions projecting from the face of said head, and cooperating means for carrying rearwardly and ejecting material cut by said cutting members from the body, the combination with said bit of a starting bit comprising a shank portion, adapted to be inserted in the leading end of the cylindrical body bore, and a relatively flat pointed cutting member mounted on the leading end of said bit shank, projecting forwardly therefrom and provided with rearwardly outwardly sloping shoulders adapted to seat against the shoulder portions of the cutting members on the face of said cylindrical body upon rotation of said bit body.

2. In a rotary bit for drilling concrete and the like, of the class including an elongated bored cylindrical body having a head at its leading end provided with a plurality of generally radially disposed cutting members including shoulder portions projecting from the face of said head, and cooperating means for carrying rearwardly and ejecting material cut by said cutting members from the body, the combination with said bit of a starting bit comprising a shank portion, adapted to be inserted in the leading end of said bore, a head mounted on the leading end of said bit shank, and generally radially disposed cutting members mounted on said head having a point at their leading end, and provided with shoulders projecting from said head and adapted to seat against the shoulder portions of the cutting members on the face at the leading end of said cylindrical body upon rotation of said body, for the purposes described.

3. In a rotary bit for drilling concrete and the like, of the class including an elongated bored cylindrical body having a head at its leading end

provided with a plurality of generally radially disposed cutting members including shoulder portions projecting from the face of said head, and cooperating means for carrying rearwardly and ejecting material cut by said cutting members from the body, the combination with said bit of a starting bit, comprising a shank portion adapted to be inserted in the leading end of the cylindrical body bore, and a relatively flat pointed cutting member mounted on the leading end of said bit shank, projecting forwardly therefrom and provided with rearwardly outwardly sloping shoulders terminating in portions parallel to the axis of said bit shank, adapted to seat against the shoulder portions of the cutting members on the face of said cylindrical body.

4. In a rotary bit for drilling concrete and the like, of the class including an elongated bored cylindrical body having a head at its leading end provided with a plurality of generally radially disposed cutting members including shoulder portions projecting from the face of said head, and cooperating means for carrying rearwardly and ejecting material cut by said cutting members from the body, the combination with said bit of a starting bit comprising a shank portion adapted to be inserted in the cylindrical body bore at the leading end thereof, and a cutting member, permanently mounted in a slot at the leading end of said bit shank, said cutting member being relatively flat and provided with a point at its leading end and rearwardly and outwardly sloping shoulders adapted to seat against the shoulder portions of the cutting members on the face of said cylindrical body.

35

5. In a rotary bit for drilling concrete and the like, of the class including an elongated bored cylindrical body having a head at its leading end provided with a plurality of generally radially disposed cutting members including shoulder portions projecting from the face of said head, and cooperating means for carrying rearwardly and ejecting material cut by said cutting members from said body, the combination with said bit of a starting bit comprising a shank portion adapted to be inserted in the cylindrical body bore at the leading end thereof, and a cutting member, mounted on the leading end of said bit shank, said cutting member being relatively flat, embedded in said bit shank and provided with a point at its leading end and rearwardly and outwardly sloping shoulders terminating in shoulders parallel to the axis of said bit shank which are adapted to seat against the shoulder portions of the cutting members mounted on the face at the leading end of said cylindrical body.
